UNITED STATES PATENT OFFICE.

JOHN BIRNIE, JR., OF BIRNIE, MANITOBA, CANADA.

SHOCKING MACHINE.

Application filed April 26, 1920. Serial No. 376,688.

To all whom it may concern:

Be it known that I, JOHN BIRNIE, Jr., of the town of Birnie, in the Province of Manitoba, Canada, have invented certain new and useful Improvements in Shocking Machines, of which the following is the specification.

The invention relates to improvements in shocking machines and the general object of the invention is to provide a machine attached to and carried by the customary harvester or binding machine and designed to receive the sheaves discharged from the binder, form them into a shock and deposit the formed shock on the ground in a standing position and firmly planted.

A further object of the invention is to construct the shocking machine so that it is entirely automatic in its operation and does not depend, in any way, upon the driver of the binder and further such that it is self driving, that is to say, does not depend on any of the binder driving mechanism for driving purposes.

A still further object is to provide a forward dumping shock basket designed after it has been dumped to remain with the shock for a predetermined interval, thereby steadyng the deposited shock.

A still further object of the invention is to provide an automatically operated means for initially delivering the sheaves from the deck to the basket and afterwards for stopping delivery of the ejected sheaves during the interval that the basket is dumping and returning.

A further object of the invention is to provide packers associated with the basket for pushing the sheaves into the basket, these being timed with the binder discharge arms and being associated with a trip arm carried by the basket and designed upon the basket being properly filled with sheaves to automatically set the basket in operation to dump the shock.

A still further object is to provide a timing device arranged to cause the basket to return to the initial sheaf receiving position after dumping the contained shock.

With the above more important and other

minor objects in view, which will become more apparent as the description proceeds, the invention consists essentially in the arrangement and construction of parts hereinafter more particularly described and later pointed out in the appended claims, reference being had to the accompanying drawings in which:

Fig. 1 represents a front view of the shocker attached to the binder and in the sheaf receiving position.

Fig. 2 represents a plan thereof.

Fig. 3 represents a side view of the shocker looking at it from the binder side and showing it in dotted outline in dumped position.

Fig. 4 represents a side view of the outer side of the shocker, or the side away from the binder.

Fig. 5 represents a plan view of the shocker in the dumped position.

Fig. 6 represents a vertical sectional view through the basket, the section being taken at 6—6 Fig. 4, and looking in the direction indicated by the applied arrow.

Fig. 7 represents an enlarged detailed view of the link connection between the operating rods on the top of the basket.

Fig. 8 represents an enlarged detailed sectional view through part of the retarder operating mechanism, the section being taken at 8—8 Fig. 1 and looking downwardly.

Fig. 9 represents a sectional view at 9—9 Fig. 2.

Fig. 10 represents an enlarged detailed view of part of the clutch.

Fig. 11 represents a plan view of the parts appearing in Fig. 10.

Fig. 12 represents a side view of a further part of the clutch.

In the drawings like characters of reference indicate corresponding parts in the several figures.

1 represents the main frame of a binding machine or harvester, 2 the master or bull wheel thereof and 3 the deck, the deck carrying the customary discharge arms 4 mounted on the discharge arm shaft 5.

The above parts are of ordinary construc-

75

85

80

90

95

100

tion and they are well understood are not herein further described.

To the binder frame I secure permanently, such as by bolting, a pair of side brackets 6 and 7 which support in the horizontal position a substantially rectangular main shocker frame 8. Forwardly to this frame I secure permanently a bearing plate 9 which is fitted with front and rear bearings 9' and 9^x (see Fig. 5), in the rear or inner one of which I mount a countershaft 10 which supports pivotally a pair of rearwardly extending equal length side arms 11 and 11^x, the rear ends of which carry a driving shaft 12 to which I secure a driving wheel 13 and a chain wheel 13'.

14 represents a bridge or arch extending across the shocker frame in a location slightly in advance of the shaft 12 and 15 and 15' are two upstanding guide rods attached to the side members 11 and 11^x and having their upper ends passing slidably through the arch 14. Cushion springs 15^x and 15² are mounted on these rods between 20 the side arms and the arch, these serving to continuously press the wheel 13 down towards the ground so that it will always ride the ground regardless of the variation in the elevation of the shocker frame. The inner 25 end of the counter-shaft is fitted with a clutch indicated generally by the reference character A and comprising what might be termed a loose member 16 and a fixed member 17, the fixed member being permanently secured to the shaft whilst the loose member is freely mounted thereon and is formed integral with a chain wheel 16' connected by a chain 16^x to the chain 30 35 wheel 13'.

40 The clutch is best shown in Figures 10, 11 and 12, the fixed member appearing in side elevation and plan view in Figures 10 and 11 and the loose member in side elevation in Figure 12. This clutch is of common construction, the fixed member presenting a rim 17' provided with a pair of outstanding diametrically opposing fins 17^x and 17^y and a pair of diametrically opposing slots 18 and 18' and fitted interiorly with a pair of pivoted T-shaped rocker arms 19 and 19' connected by a link 19^x and having one of the arms connected by a spring 20 to the hub of the clutch member and the other of the arms fitted with a roller 20' located outside of the rim.

The loose member 16 is rotatably mounted on the countershaft and is fitted with a rim provided on the interior side with a plurality of seats or notches 21 designed to receive the roller. Associated with the clutch is a trip lever 22 having a striking end 22' and the inner end supplied with a roller 22* designed to enter the slots 18 and 18' and also to ride the fins.

65 By observing Fig. 10 and considering the

loose clutch member in position such that it contains the roller 20' it will be apparent that when the trip lever is in the position shown in full outline the roller 22^x serves to hold the upper rocker arm back (this against the action of the spring 20) and thereby holding the roller 20' clear of the seats 21. Consequently the loose clutch member can rotate freely and is driven by the chain wheel 13'. However, should the free end of the trip lever be struck downwardly against the action of the pressure spring 22^y the rocker arm 19 will immediately swing to the dotted position and the roller 20' will engage one or other of the 80 notches 21 and thereby cause the clutch member 17 to turn with that 16 and accordingly impart rotary movement to the countershaft from the rear axle 12.

The countershaft will be driven for half a revolution, this being explained by the fact that immediately the lever 22 is tripped the clutch member 17 starts to rotate and the roller 22^x dropping back on to the fin 17^x rides this fin and the face of the rim until the slot 18 is presented when it strikes the rocker bar 19' withdraws the roller 20' and passes into the slot 18, thereby locking the roller 20' in its released position and stops in the half revolution, the further driving of the countershaft.

I have not entered into a minute description of this clutch as I have already stated it is now in use and it is believed that a general description of its construction and working will be sufficient for the purpose of this description. Here I might also state that in so far as my machine is concerned any clutch which can be tripped and will reset in half a revolution for further tripping will accomplish my object in so far as the clutch is concerned. 100 105

23 represents the main basket supporting arm, this arm being pivotally attached to the front end of the shocker frame and extending upwardly and outwardly and suspending the basket B in an elevated position above and to the side of the shocker frame. The basket arm has the lower end in the form of a pivot shaft 24 which is 110 rotatably mounted in the bearing 9'. From this shaft the arm extends vertically upwardly as indicated at 23', then horizontally outwardly as indicated at 23^x then horizontally rearwardly as shown at 23° and finally 120 downwardly in a vertical direction as indicated at 23² where it is permanently secured at 25 to the top of the basket B and in a central location.

From this description it will be seen that 125 this arm is of a double L-shape, both the L-shaped parts being contained in vertical planes and with the one extending in a direction at right angles to the binder and the other going rearwardly and parallel with 130

the binder. The outer ends of the shaft 24 and the countershaft 10 are fitted with cranks 26 and 26' connected by a link 26" and the crank 26 is considerably longer than crank 26' so that a complete rotation of the crank 26' simply rocks the crank 26 forwardly and backwardly and does not turn it a complete revolution. Actually in a complete revolution of the crank 26' the crank 26 is designed to swing ninety degrees, this action turning the basket supporting arm which it controls from an upright position as shown in Fig. 3 to a horizontal position as shown in dotted outline in Fig. 3, which latter position is the dumped position of the basket.

Here I wish it to be noted that owing to the formation of the clutch both the countershaft and the shaft 24 are automatically locked against movement when the basket arm 23 is in the upright and in the horizontal positions and provision has to be made as later described for unlocking the arm 23 to permit the basket to pass to dumping position and also to allow it to return to the initial sheaf receiving position after dumping.

The basket is of an open ended cone shape and presents a side filling opening C and is mounted with the large or butt end to the front. It is formed from two suitably reinforced metallic sections 27 and 27' connected together by suitable side hinges 27" at the side remote from the binder.

From this it will be seen that the top half is stationary, being connected directly at 25 to the arm 23, whilst the bottom half is free to swing, turning at the hinges. The hinged or underside of the basket is controlled by a bowed controlling lever 29 pivotally secured at 29' to the top of the basket section 27' and having the lower end connected by a pin 29" to the lower section 27 of the basket in a location below the hinge. The latter end of the lever is slotted as shown at 30 to receive the pin and in a location directly above the pivot point 29' the lever is supplied with an outstanding arm 30' which is connected by a comparatively strong tension spring 31 to the basket arm 23, the spring having a natural tendency to swing the lower end of the arm out and open the lower half of the basket (see Fig. 6). This tendency of the spring however is controlled by a locking roller 32 normally engaged in a receiving notch 32" provided in the upper end of the lever, the roller being carried by an arm 32' pivotally mounted on the basket as indicated at 32' and having the end remote from the roller connected to the basket by a compression spring 33 designed to force the roller normally from the notch. The arm 32' is provided with an inclined portion 32" located between the pivot point 32' and the spring 33 and the inclined part

of the lever is straddled by a standard 34 fitted with a roller 35 riding the basket and designed in the locked position as shown in Fig. 6 to counteract the action of the spring 33 and consequently retain the roller 32 in the locked position within the notch 32" with the parts so set that no movement can occur in the arm 29 with the result that the under half of the basket remains in the closed position. It will be observed however that should the standard be moved towards the spring 33 the spring will be allowed to expand, this owing to the inclined part 32", and consequently the roller 32 will be freed from the notch and thereby allow the spring 31 to actuate the lever 29 and open the under half of the basket. The parts associated with and controlling the movement of the standard are now described:—

36 represents a bracket extending from the standard towards the arm 29 and providing a bearing for a swinging shaft 37 pivoted at 37' to the top of the basket and having the rear end fitted with a roller 37" riding the adjoining face of the lever 29. The other end of the shaft 37 is connected by a pivot pin 38 to a cross rod 39, the outer end of which is slidably carried by the inner bracket of a pair of brackets 40 and 41 mounted on the top of the basket and the inner end of which is connected to one end of a substantially U-shaped lever 42 pivotally secured to the basket arm 23. To the other end of the latter lever I attach a link 43 which is connected pivotally to a further horizontally disposed lever 44 pivotally attached to the basket arm and having the free end thereof connected to an operating bar 45 pivotally anchored at 46 to the shocker frame in a location to the rear of the shaft 24 (see Fig. 5).

The above arrangement provides for the releasing of the swinging part 27 as the basket passes the dumping position as it will be apparent that as the basket arm swings forwardly there will be a pull exerted in the bar 45 which will act through the various connections to force back the standard 34 and consequently allow the spring 33 to extend and release the roller 32 from the lever 29, the said lever then operating under the action of the spring 31 to open the swinging half of the basket.

Here I might explain also that in the turning action of the basket from dumping to sheaf receiving position this movement is reversed and the upper end of the lever 29 is crowded back by the roller 37" until the section 27 of the basket has been closed and locked by the roller 32 re-entering the notch 32".

The tripping of the basket is effected automatically coincident with the filling thereof with sheaves and the tripping mechanism embodies the parts now disclosed.

47 represents a trip rod connected by a hinge 47^x to the basket and having a knee 47' extending normally through the slot 48 provided in the basket. The upper end of this rod is attached pivotally to a crank 49' located at the rear end of a short shaft 49 carried by the basket arm and the forward end of the crank is fitted with a crank 49^x connected by a link 50 with a crank 51' located at the end of a further rod 51 positioned at right angles to the shaft 49 and carried by the member 23^x of the basket arm. The innermost end of the latter rod is fitted with a kicker 52 which normally engages the upper end of a vertically disposed operating rod 53 carried by the vertical portion 23' of the basket arm. The lower end of the rod 53 rides the free end of the trip lever and a coiled spring 54 holds the said rod normally up, the spring engaging the collar 55 fastened to the rod.

From this construction it will be seen that as the basket becomes filled with sheaves the knee 47' will be pressed out and this movement will effect through the various connections a down swinging of the kicker 52, a down movement of the rod 53 and the consequent release of the clutch lever which will immediately cause, through the engagement of the clutch members, a rotation in the countershaft and the forward swinging of the basket arm, which latter movement turns the basket into shock dumping position.

As soon as the basket reaches the dumping position the swinging section 27 thereof opens in the manner herein before disclosed to release the shock and coincident with the freeing of the shock the knee is free to regain its normal position, thereby releasing the clutch lever and disconnecting the clutch members, with the result that the basket stays in the dumped position until the clutch members are again engaged by a timing mechanism now described.

45 The brackets 40 and 41 herein before mentioned provide a bearing for a shaft 56 on which I have mounted a timing wheel 57 and a gear wheel 58, the gear wheel meshing with a further gear wheel 59 located on a cross shaft 60 also carried by the brackets. The inner end of the cross shaft is mounted in a bearing 61 secured to the basket arm and the end of the shaft adjoining the said bearing is fitted with a striker 62 which is designed in the turning of the shaft to engage a vertically disposed slidably mounted resetting rod 63 carried by the basket arm and normally held up by a spring 64 similar to that 54.

60 In the forward dumping of the basket the wheel 57 will engage the ground (see dotted outline Fig. 3) and will accordingly be turned, with the result that the striker 62 will come around, hit and pass the upper end of the rod 63, which at this time is

more or less in the horizontal position as shown in dotted outline in Fig. 3. The end movement so produced in the rod 63 is utilized to trip the clutch as it will be observed in Fig. 3 that in the dumped position of the basket the said trip rod in moving backwardly will strike the free end of the trip lever and consequently disengage the clutches.

This timing appliance accordingly provides for the basket remaining in the dumped position a short time to steady the shock as the wheel 57 has to turn one revolution before the striker 62 strikes. Immediately however the striker strikes the rod 63 the clutch lever is thrown in a direction which will engage the clutches and cause the countershaft to rotate and return the basket arm to its original upright position, this movement being transmitted through the link 26^x.

When the basket arm has reached the upright position, and this in half a revolution of the clutch, the trip lever roller 22^x drops into one of the slots and simultaneously releases the roller 20' from the clutch member 16, with the result that further turning of the countershaft is stopped and the basket arm becomes locked in the upright position with the basket set ready to receive the sheaves.

The time which the basket remains in the dumping position can be gauged by varying the ratio of the gears 58 and 59 as will readily be understood.

The open space between the basket and the deck is spanned by combination delivery and retarding prongs 65, the outer ends of which pass into the basket through the opening C and the inner ends of which are secured to a carrying shaft 66 supported on suitable bearings carried by stationary standards 67 and 68 extending upwardly from the brackets 6 and 7. A crank 69 is secured to the forward end of the latter shaft and is connected by a link 70 to a second crank 71' extending from a lower shaft 71 carried by a bearing 72 permanently secured to the lower end of the standard 67.

73 represents a further crank permanently attached to the shaft 71 and connected to a pair of pivotally connected break joint links 74 and 75, the link 75 being attached to a stationary arm 76 extending from the bearing 72. 77 represents a pulling arm permanently connected to the upright portion 23' of the basket arm and having the free end pivotally fastened at 78 to the links.

In the normal position of the basket the prongs 65 are positioned as shown best in Fig. 1 and are designed to deliver the sheaves from the deck to the basket. However, during the interval that the basket

70

75

80

85

90

95

100

105

110

115

120

125

130

is being dumped I desire to stop the oncoming sheaves and to this end the mechanism associated with the prongs has been provided, such being operated by the forward 5 swinging of the basket arm and effecting through the pulling arm 77 the breaking of the joint between the links and the consequent swinging of the crank 73 in a direction which will shift the link 70 upwardly 10 and accordingly raise the prongs clear of the basket and to a position such that they will hold any sheaves that may be discharged from the deck when the basket is being dumped.

15 Obviously the back swinging of the basket supporting arm reverses the movement just described and causes the prongs to go back to their normal delivering position when the basket has returned to its 20 sheaf receiving position.

To the upper side of the basket in a location above the opening C I provide a plurality of packers 79 all extending from a common supporting shaft 80 previously 25 mounted on the basket. The packers are held normally in their up position by a spring 81 attached to the basket and to a crank like arm 82 extending from the shaft. 83 represents a fixed arm extending towards 30 the binder from one of the shaft bearings and carrying pivotally a lever 84, the outer end of which is connected by a link 85 to the crank arm 82 and the free end of which, or that next the binder, is designed to 35 be engaged by a roller 86 located at the end of a crank 87 secured to the discharge arm shaft 5.

Here I might explain that on the present binders the discharge arm shaft is rotated by the binder mechanism and is designed to discharge a sheaf from the deck each rotation of the shaft. Accordingly 40 each time the discharge arm shaft rotates the roller 86 is engaged with the free end of the lever and this immediately after the discharge of the sheaf from the deck, which action causes the other end of the lever 84 to pull down on the crank 82 and consequently 45 swing the packers inwardly towards the basket and press the passing sheaf into the basket.

In the actual operation of the shocker the sheaves delivered to the basket are formed by the basket into a shock and about the 50 time the basket is becoming filled there will be a pressure exerted by the packers and through the sheaves to the knee 47' and this pressure will effect the out pushing of the knee and the consequent tripping of the 55 clutch to set the basket arm in motion as already described. The instant the basket arm starts it exerts two pulls, one through the arm 77 to raise the prongs 65 and retard the sheaves and another through the 60 bar 45 to release the swinging part 27 of the basket, the greater part of the latter motion as produced by the pulling arm taking place when the basket arm is approaching the horizontal position. Once 65 the basket is in the dumping position and the shock has been released by the back swinging of the section 27 it remains there until the timing wheel has turned one revolution, at which time the swinging arm is 70 swung back to the initial position by the throwing in of the clutch which is brought about by the trip rod 63. The instant the basket arm takes its original upright position the clutch goes out of commission and the movement stops with all parts reset 75 and ready for further delivery of sheaves.

The front or large end of the basket carries a plurality of vertically disposed fingers 88 which cross the basket and are permanently secured to the stationary section 80 thereof. These fingers prevent the formed shock from sliding bodily out of the basket when it is being dumped. In the dumped position of the basket they simply withdraw in the onward movement of the machine from beneath the planted shock.

85 What I claim as my invention is:—

1. The combination with a shocker frame, of a basket arm having one end pivotally mounted on the shocker frame, and the other end elevated and located at the side of the frame, a horizontally disposed sheaf receiving and shock forming basket permanently suspended from the elevated end of the arm and means for swinging the arm forwardly 90 and backwardly at predetermined instants to dump the basket and return it to the initial sheaf receiving position.
2. The combination with a shocker frame, of a basket arm pivotally mounted for forward and rear swinging in respect to the frame, said arm extending normally upwardly, then outwardly from the frame, then rearwardly and finally downwardly, a horizontally disposed sheaf receiving and shock forming basket permanently suspended from the downturned end of the arm and provided on the frame side with a filling 95 opening and means for swinging the arm forwardly to bring the basket into dumping position and rearwardly at a predetermined time to return the basket to the original receiving position.
3. The combination with a shocker frame, of a basket arm having the lowermost end rotatably mounted on the front end of the shocker frame, said arm extending normally upwardly, then outwardly from the frame, then rearwardly and finally downwardly, a normally horizontally disposed sheaf receiving basket permanently suspended centrally from the downturned end of the arm and having a filling opening in the side thereof towards the shocker frame, automatically 100 operated means for swinging the basket for-

wardly to dumping position upon the basket becoming filled with sheaves and timed means for automatically returning the basket to sheaf receiving position after the contained shock has been dumped.

4. The combination with a shocker frame, of a basket arm pivotally mounted on the frame and extending upwardly, then outwardly in respect to the frame, then rearwardly and finally downwardly, a normally horizontally disposed sheaf receiving and shock forming basket having a side filling opening therein and permanently suspended from the downturned end of the arm and formed from a top stationary section secured to the arm and a bottom swinging section attached to the stationary section, means normally locking the swinging section of the basket against movement in the sheaf receiving position of the basket, automatic means for swinging the basket arm forwardly to move the basket into dumping position, means for releasing the swinging basket section to open as the basket approaches dumping position and to close the swinging section as the basket moves back to sheaf receiving position and timed automatic means for returning the basket arm to its initial position, the return movement occurring a short interval after the shock has been dumped.

5. The combination with a shocker frame, of a basket arm pivotally mounted on the frame and extending upwardly, then outwardly in respect to the frame, then rearwardly and finally downwardly, a normally horizontally disposed sheaf receiving and shock forming basket having a side filling opening therein and permanently suspended from the downturned end of the arm and formed from a top stationary section secured to the arm and a bottom swinging section attached to the stationary section, means normally locking the swinging section of the basket against movement in the sheaf receiving position of the basket, automatic clutch controlled driving means for swinging the basket arm forwardly to pass the basket into dumping position, said means being set in action upon the basket becoming filled with sheaves and thrown out of commission when the basket reaches dumping position, automatically operated means for releasing the basket swinging section to open upon the basket approaching dumping position and to close the basket section as the basket returns to sheaf receiving position and timed automatically operated means for throwing the clutch into commission to return the basket arm from the dumping to the original upright position, said means being actuated a predetermined time after the shock has been dumped.

6. The combination with a sheaf receiving and shock dumping basket, of rotatably

mounted means carried by the basket and designed to engage with and be rotated by the ground in the dumped position of the basket and to directly control the time the basket remains in the dumped position.

7. The combination with a sheaf receiving and shock forming basket, means for suspending the basket and an operating mechanism for dumping and returning the basket, of a timing wheel carried by the basket and engageable with the ground in the dumped position of the basket and operating connections between the timing wheel and the operating mechanism and controlled by the wheel and designed to actuate the operating mechanism to effect the return of the basket at a predetermined time after dumping.

8. The combination with a binder frame and the deck thereof, of a shocker frame permanently suspended from the binder frame at the deck side, a countershaft rotatably mounted on the forward part of the shocker frame, a pair of side arms having their forward ends pivotally swung from the countershaft, a driving shaft rotatably mounted in the rear ends of the arms, a ground wheel secured to the driving shaft and a driving connection between the driving shaft and the countershaft.

9. The combination with the binder frame and the deck thereof, of a shocker frame permanently suspended from the binder frame at the deck side, a countershaft rotatably mounted on the forward part of the shocker frame, a pair of side arms having their forward ends pivotally swung from the countershaft, a driving shaft rotatably mounted in the rear ends of the arms, a ground wheel secured to the driving shaft, springs normally pressing the side arms downwardly a driving connection between the driving shaft and the countershaft and a clutch associated with the countershaft.

10. The combination with the discharge arm shaft of a binding machine and a normally horizontally disposed sheaf receiving and shock forming basket having a side opening therein, of a plurality of packers mounted on the basket above the opening, a spring normally holding the packers up, actuating means carried by the basket and connected with the packers and extending towards the discharge arm shaft and a striking crank secured to the discharge arm shaft and designed to engage with and actuate the actuating mechanism once each revolution of the discharge arm shaft and effect the down swinging of the packers.

11. In a shocking machine, the combination with a normally horizontally disposed sheaf receiving and shock forming basket and means for turning the basket to dump the contained shock, of means protruding into the basket and designed to be engaged

and shifted by a sheaf upon the basket becoming filled and to set the basket actuating means into operation.

12. The combination with a normally horizontally disposed sheaf receiving and shock forming basket provided with a side filling opening and means for swinging the basket to dumping position, of a trip rod associated with the basket and protruding into the same at the side remote from the filling

opening and connected with the basket operating mechanism whereby in the outward pressing of the trip rod the operating mechanism is put into action.

Signed at Neepawa this 8 day of April 15 1920.

JOHN BIRNIE, JUNIOR.
